US00D862379S

(12) **United States Design Patent** (10) **Patent No.:** **US D862,379 S**
Au (45) **Date of Patent:** ** *Oct. 8, 2019

(54) **PANEL RAIL SADDLE DEVICE FOR SOLAR MODULE**

(71) Applicant: **NEXTracker Inc.**, Fremont, CA (US)

(72) Inventor: **Alexander W. Au**, El Cerrito, CA (US)

(73) Assignee: **NEXTRACKER INC.**, Fremont, CA (US)

(*) Notice: This patent is subject to a terminal disclaimer.

(**) Term: **15 Years**

(21) Appl. No.: **29/624,181**

(22) Filed: **Oct. 30, 2017**

Related U.S. Application Data

(63) Continuation of application No. 29/527,987, filed on May 22, 2015, now Pat. No. Des. 804,407, which is a continuation of application No. 14/489,416, filed on Sep. 17, 2014, now Pat. No. 10,008,975.

(57) **CLAIM**

The ornamental design for panel rail saddle device for solar module, as shown and described.

DESCRIPTION

FIG. 1 is a perspective view illustrating a panel rail saddle device for solar module detailing our new design;

FIG. 2 is a front view thereof;

FIG. 3 is a back view thereof;

FIG. 4 is a first side view;

FIG. 5 is a second side view thereof;

FIG. 6 is a top view thereof; and,

FIG. 7 is a bottom thereof.
